UNITED STATES PATENT OFFICE.

CHARLES FUNK, OF GENEVA, SWITZERLAND.

RING-BAND FOR WATCH-MOVEMENTS.

No. 892,147.

Specification of Letters Patent.

Patented June 30, 1908.

Application filed October 23, 1906. Serial No. 340,134.

To all whom it may concern:

Be it known that I, CHARLES FUNK, citizen of the Republic of Switzerland, residing at Geneva, in the canton of Geneva, Switzerland, have invented certain new and useful Improvements in Ring-Bands for Watch-Movements, of which the following is a specification.

The present invention relates to an improved ring-band adapted to connect a Swiss watch-work with an American watch-case, the ring band comprising a cylindrical body portion provided with an interior circular bearing or flange intended to support the usual rim of the plate of a Swiss watch movement, and an exterior circular bearing or flange intended to be supported upon the inner rim of the center of an American watch-case, the transverse section of the improved ring-band being approximately a **Z**.

The drawing shows the improved ring band connecting a Swiss watch movement having its dial set in a bezel, with the case center of an American case.

In the construction shown in the drawing, the plate *a* is provided with a dial *b* set in a bezel of a ring *c* locked on the plate *a* and the plate *a* is provided with a circular rim *a'*.

My improved ring band comprises a cylindrical body portion *d*, corresponding in its inner diameter with the outer diameter of the said circular rim *a'*. At one end the body portion *d* is provided with an internal flange *d'* adapted to engage the said circular rim *a'*

and thereby support the plate *a*, and at the other end the body portion *d* is provided with an external flange *d²* in a different plane to the internal flange *d'* and adapted to engage and to be supported upon an internal circular rim *e'* on the watch case center *e* of an American watch case.

The improved ring-band may be made with a depending circular projection adapted to surround the bridges of the watch works, as shown in dotted lines in the drawing, in order to prevent the dust entering the movement.

I claim as my invention:

The combination with a watch case center having a circular rim and a watch movement plate having a circular external rim, of a ring band comprising a cylindrical body portion *d*, an internal flange *d'* at one edge thereof and an external flange *d²* at the front edge thereof, the ring band receiving the movement plate with the rim of the movement plate resting against the flange *d'* and the flange *d²* resting upon the rim of the watch case center, and a ring *c* having a dial bezel surrounding the movement plate and received therewith within the ring band.

In testimony whereof I have affixed my signature in presence of two witnesses.

CHARLES FUNK.
